UNITED STATES PATENT OFFICE.

JOSEPH MILES RHODES, OF HALLS, TENNESSEE.

ICE-BOX.

1,385,274.

Specification of Letters Patent. Patented July 19, 1921.

Application filed May 3, 1920. Serial No. 378,500.

To all whom it may concern:

Be it known that I, JOSEPH MILES RHODES, a citizen of the United States, residing at Halls, in the county of Lauderdale and State of Tennessee, have invented certain new and useful Improvements in Ice-Boxes; and I do hereby declare the following to be a full, clear, and exact description of the invention, such as will enable others skilled in the art 10 to which it appertains to make and use the same.

The present invention relates to improvements in ice boxes, and has for an object to provide an apparatus adapted both for 15 the storage of bottled goods which it is desirable to keep immersed in cold water, and for perishable articles to be preserved by the contact therewith of cold air without the use of water.

Another object of the invention lies in providing an improved ice box in which large 20 quantities of bottled goods of different varieties may be kept in a cold condition in readiness for drinking purposes and which admits of the ready removal of the bottles from 25 the apparatus.

A further object of the invention resides in providing an improved apparatus including a box or chest having trays and shelves 30 mounted therein in connection with a false or latticed bottom, and guides which are constructed in sectional units adapted to be installed in a usual form of box without alteration in the construction thereof.

A still further object of the invention resides in providing an improved ice box having means for controlling the height of the cooling water therein, and for the draining off of the water when the apparatus is used 35 40 to contain articles of a perishable nature to be kept by contact with cold air without the aid of water.

In the accompanying drawings forming a part of this application, and in which similar 45 reference symbols indicate corresponding parts in the several views:

Figure 1 is a perspective view of an improved ice box constructed in accordance with the present invention, having the lids thereof lifted, one of such lids being partially broken away.

Fig. 2 is a longitudinal central sectional view taken through the improved ice box.

Fig. 3 is a transverse sectional view taken on the line 3—3 in Fig. 2.

Fig. 4 is a top plan view of the ice box with the covers lifted and broken away, and with the trays and shelves removed.

Fig. 5 is a vertical sectional view taken on the line 5—5 in Fig. 2.

Fig. 6 is a perspective view of one of the trays.

Fig. 7 is a fragmentary perspective view of a portion of a guide unit.

Fig. 8 is a transverse sectional view through one of the trays; and

Fig. 9 is a perspective view of one of the partitions for the trays.

Referring more particularly to the drawings, 1 designates an ice box or chest of a usual form having a pair of lids 2 and 3 hinged thereto, as indicated at 4 and 5, and constructed in a usual manner to fit tightly the upper open end of the chest 1, the lids being preferably faced on their inner 70 sides with galvanized metal.

A division bar 6 fits within recesses 7 and 8 made in the top of the chest 1, and extends transversely across the central portion of the box, providing an abutment for the adjacent edges of the doors 2 and 3. The bar 6 is readily removable from the recesses 7 and 8 to permit of the withdrawal of the ice container. The bottom and side walls of the chest 1 are also preferably faced with 75 80 85 sheet galvanized metal, as shown in the drawings.

A drain pipe 9 connects with the bottom of the box and also with a pipe 10 running forwardly beneath the box, and having connection to the lower end of an upright pipe 11. Branch pipes 12 and 13 connect with the upper end of the pipe 11, the pipe 12 being in communication at a relatively high level with the interior of the box and providing 90 95 for the automatic draining off of water in the box which rises to the level of the open end of this pipe 12. The pipe 12 is at all times in open communication with the interior of the box at a desired elevation, and it also communicates uninterruptedly with the pipes 11 and 10 and with the drain pipe 9, so that the effect of this arrangement of pipes is to preserve the water level in the chest 1 substantially constant, and it avoids 100 105 the rise of the liquid above this level, insur-

ing against accidental overflow of the box. The other branch pipe 13 connects with the interior of the box at a substantially lower level than the pipe 12, and includes a valve 14 operated by a hand wheel 15 or other suitable device. The valve 14 is normally kept closed in order to prevent the escape of the water from the box through this low connection, but it may be opened by means 10 of the hand wheel 15 to drain off the water above this elevation for a purpose later to be described.

Within the ice chest is a false or latticed bottom made up in two longitudinal sections 15 or units comprising pairs of longitudinal rails 16 and 17 and cross pieces 18 and 19 connected between the rails and secured in any desired manner beneath the same. The adjacent ends of the cross pieces 20 18 and 19 project beyond the proximate rails 16 and 17, and are arranged to abut together in the manner shown in Fig. 4 to properly position the two sections in order that they form continuations of one another and provide an even and uniform bottom.

The outer longitudinal rails 16 and 17 are secured to stirrups 20 and 21 which are provided by the lower right angularly bent 30 ends of hangers 22 and 23. As indicated in Fig. 7, the stirrups are preferably provided with perforations 24 in which to receive fastening means for securing the rails thereto.

35 The upper ends of the hangers 22 and 23 are secured as by riveting, or other desired means, in recesses 25 provided in stile bars 26 and 27 which are removably mounted in the box 1 near the upper open end 40 thereof. Perforations 28 are made in the stile bars to receive screws or other fastening means by which they are removably secured to the chest.

Guide rails 29 and 30 are also provided 45 in conjunction with the stile bars 26 and 27 and with the bottom units, the same being curved at their upper portions as indicated at 31 in Fig. 7. The upper ends of the guide bars are overturned at right angles, as indicated at 32, and are provided 50 with perforations to receive rivets or other suitable fastening means 33 by which they are secured in recesses 34 made in the stile bars 26 and 27.

55 A series of perforations 35 are provided in the guide bars 29 and 30 to receive pins 36 and 37 for supporting shelves 38. The lower ends of the guide bars 29 and 30 are similarly overturned, as indicated at 39 in 60 Fig. 7, and provided with perforations 40 to receive fastening means such as the screws 41 by which they are secured to the upper faces of the cross pieces 18 and 19. The guide bars 29 and 30 extend inwardly of 65 the hangers 22 and 23 and are spaced apart

suitable distances and in pairs, in order to receive therebetween the shelves 38 or trays.

These trays are more particularly shown in Figs. 6 and 8, and comprise end walls 42 and 43 and side walls 44 and 45 having 70 numbers of perforations 46 and 47 therein to allow of a free flow of the cooling water therethrough and in contact with the articles which are held on the bottom 48 of such trays.

75 The bottoms 48 of the trays are placed at a considerable elevation above the lower edges of the tray walls to permit the trays to rest one upon another in the manner indicated in Figs. 2 and 3, without interference from the necks of the bottled goods supported therein. These necks extend above the tops of the tray walls in order that they may be readily grasped and removed.

80 The bottoms 48 of the trays are supported by suitable cross pieces 49 extending between the side walls 44 and 45, and the ends of such bottoms may be soldered to the end walls 42 and 43 or otherwise connected thereto.

85 The longitudinal edges 50 of the bottoms 48 are preferably reinforced by turning such edges beneath the bodies of the bottoms, this construction also being of advantage in providing spaces 51 and 52 at the sides of the bottoms to permit a transfer of the cooling liquid downwardly from the interior of the trays, through such spaces. The bottoms and tops of the trays are preferably reinforced, as indicated at 53, by rolling the same. This gives additional strength and also provides relatively large surfaces for supporting one tray upon another.

90 In the trays may be placed partitions, such for instance as shown in Fig. 9, consisting of plates 54 of substantially the width of the trays, and being provided at the opposite vertical edges thereof with strips 55 and 56 having outwardly curled 95 upper edges 57 and 58 constructed and positioned for engagement with the upper rolled edges of the side walls 44 and 45 of the trays. The partitions are slidable along the upper edges of the side walls to the desired position within the trays, and may be quickly removed by lifting the same directly upward. These partitions are especially useful for segregating one kind of bottled goods, for instance ginger ale, from another kind of bottled goods; or if the entire tray is devoted to a single line of goods the partitions may be removed. With goods having large sales such, for instance, as bottled coca cola, it will probably not be 100 necessary to use the partitions.

105 The ends of the bottom units may also be supported by hangers 59 and 60, if desired, which are constructed in the same manner as the hangers 22 and 23, and are 110

secured at their upper ends directly to portions of the ice chest 1.

In the center of the chest is provided an ice container 61 having openings at 62 there-
5 in to permit the free flow of the water there-
from into the chest. A cover plate 63 is
also preferably provided for the ice con-
tainer 61, and the same forms a shelf above
the liquid level on which to place perishable
10 articles that would be injured if submerged.
The ice container 61 will be of a suitable
capacity and is preferably made of metal, it
being readily removable by first lifting off
the division bar 6.

15 The various trays used are also with ad-
vantage provided with handles 64 and 65
attached to the end walls 42 and 43, prefer-
ably projecting inwardly toward each other
at their upper ends. Although these trays
20 may be lifted manually from the ice chest it
is preferred to use an implement such as
indicated in Fig. 6 in the form of a bail 66
provided of rod metal bowed upwardly and
having upturned hooks 67 and 68 at its op-
posite ends. The length of the bow 66 will
25 be such as to have the hooks 67 and 68 spaced
apart a correct distance to engage the upper
bars of the handles, and the fact that the
handles project toward one another will
30 admit of the hooks being readily inserted
therewith.

In the use of the apparatus bottled goods,
for instance coca cola and the like, are
35 placed upright on the bottoms 48 of the
trays, the neck portions of the bottles pro-
jecting above the upper edge of the trays, as
indicated in dotted lines in Fig. 2, to permit
the server to readily distinguish the various
40 bottles and to grasp and remove the same

The trays with the bottled goods therein
are lowered through the top of the box
while the lids 2 and 3 are lifted, and are en-
gaged by the guide bars 29, so that they as-
45 sume correct positions, extending trans-
versely across the chest and occupy a mini-
mum of space. The lowermost trays rest
upon the bottom units while the trays above
50 rest upon the upper edges of sub-trays, the
bottoms of the higher trays being spaced a
requisite distance above the caps of the
bottles held in the lower trays.

Ice is, of course, kept in the container 61
55 in a suitable quantity for preserving the
water in the chest at a desired low tempera-
ture. Water is introduced into the chest in
any suitable manner, and it is allowed to rise
to the elevation of the pipe 12. This eleva-
60 tion is shown to be such, in Fig. 3, that it will
leave the necks and caps of the bottles in the
uppermost trays exposed above the water
level, so that the names on the caps may be
easily read by the server and the necks of
65 the bottles may be grasped without wetting
the hands. At the same time the bodies of

the bottles will be completely immersed in
the cold liquid, and this is entirely sufficient
to keep the contents at a desired low drink-
ing temperature.

Perishable articles of a character sus-
ceptible of injury by water may be placed
upon the top 63 of the ice container, and
they may also be placed upon the shelves 38
which lie above the liquid. At the same time
other of the shelves 38 may be supported
70 beneath the liquid level and may, if desired,
contain articles that are not apt to be ruined
by contact or immersion in the water such,
for instance, as canned goods, butter, etc.
Should it be desired to lower the liquid level,
75 the valve 14 may be opened, permitting of
the escape of the water through the pipe 13,
or in case it is preferred to utilize cold air
alone, the drain 9 may be opened, which is,
80 of course, closed by some suitable stopper
when the water is used.

The trays may all be lifted out of the ice
chest and the pins 36 and 37, of which there
will always be a quantity on hand, may be
placed through the perforations 35 in the
90 guide rails 29 and 30 in order to support the
shelves 38.

Articles placed upon the shelves 38 will
be kept cold by the contact therewith of the
air within the box which circulates about
95 the ice, and is kept moving by the action of
convection currents.

In case it is desired to remove the apparatus
from the ice chest for purposes of cleaning
or otherwise, the trays may be quickly lifted
100 out by use of the bails 66, and the shelves
38 together with the pins 36 and 37, are sus-
ceptible of very quick removal, after which
the various screws and other fastenings hold-
ing the stile bars 26 and the end hangers 59
105 and 60 may be withdrawn, whereupon the
two bottom sections together with the guide
rails and hangers are capable of removal as
two separate units. After the same are thor-
oughly cleaned and the interior of the box
110 washed out these parts may be subsequently
replaced and their fastening in the box re-
newed.

The partitions 54 shown in Fig. 9 are also
useful in segregating cold bottled goods
115 from the warm bottles that have just been
placed in the ice box. For instance, it is
desirable when, say two rows of the cold
bottles have been removed from any par-
ticular tray, to replenish the vacated space
120 by fresh warm bottles. In this case a parti-
tion is put in the tray to enable the server
to distinguish the cold from the warm
bottles so that he will not make the mis-
take of serving the latter. This situation
125 occurs particularly when only a bottom row
of trays are used. The partition is moved
along in the tray as more cold bottles are
withdrawn to make room for the substitu-
tion of fresh warm bottles.

The pipe 13 is a special overflow or drainage pipe to be employed only when a single row of trays is carried in the bottom of the chest as in dull seasons when a smaller quantity of bottled goods is required. The opening of the valve 14 provides for the draining off of the water above the bottom trays. When a higher water level is desired to immerse further rows of trays the valve 14 is closed and the pipe 12 brought into use.

It is obvious that those skilled in the art may vary the details of construction and arrangements of parts without departing from the spirit of my invention, and therefore I do not wish to be limited to such features except as may be required by the claims.

I claim:

- 20 1. In an ice box, a chest having an open upper end, closure means for the open end of the chest, sectional bottom units removable from the chest, sectional guide means respectively connected to said bottom sections, means for detachably connecting said guide means at the upper end of the chest, and supports for articles removably held between said guide means and independent of the same, substantially as described.
- 25 2. In an ice box, a chest, a false bottom removable from the chest, stile bars removably secured in the chest, guide rails connected between said bottom and stile bars and removable from the chest with the same, and supports for articles placed between said guide rails and removable independently thereof, substantially as described.
- 30 3. In an ice box, a chest, guide bars therein having perforations, trays adapted to be placed between said guide bars, pins for

extending in the perforations, and shelves adapted to rest on the pins, substantially as described.

4. In an ice box, a chest having guide means therein, and trays removably mounted between said guide means, said trays composed of perforated body portions, and having bottoms set up from the lower portions of the bodies to permit the trays to rest one upon another and to provide space for the projecting parts of articles held therein, substantially as described.

5. In an ice box, a chest provided with guide means, and trays removably supported between said guide means, said trays comprising body portions having perforations therein to permit the circulation of fluid and reinforced along the upper and lower edges thereof, and bottoms in the trays having the side edges thereof spaced from the bodies of the trays to permit circulation of fluid therethrough, substantially as described.

6. In an ice box, a chest having guide means therein, removable trays placed between the guide means and having handles at their upper ends projecting toward one another, and a bail having a bowed central portion with upturned hooks at its ends adapted to engage said handles to remove the parts, substantially as described.

7. In an ice box, a chest having guide means therein, trays removably mounted between the guide means, and uprights for the trays including transversely extending plates and end strips secured to the plates and having curled upper edges to engage the upper portions of the bodies of the trays, substantially as described.

JOSEPH MILES RHODES.
